UNITED STATES PATENT OFFICE.

FRANK P. D'ARCY, OF KALAMAZOO, MICHIGAN.

PORTABLE SUPPORT.

1,365,093.

Specification of Letters Patent. Patented Jan. 11, 1921.

Application filed February 7, 1919. Serial No. 275,574.

To all whom it may concern:

Be it known that I, FRANK P. D'ARCY, a citizen of the United States, residing at the city and county of Kalamazoo and 5 State of Michigan, have invented certain new and useful Improvements in Portable Supports, of which the following is a specification.

This invention relates to improvements in 10 portable supports. My improved portable support is especially designed by me for supporting electric lamps whereby they may be carried about or fastened on different objects or to the person using the lamp.

15 The main objects of this invention are:

First, to provide an improved portable support for a lamp by means of which the lamp may be supported in the proper position to deliver the light upon an object 20 such as part of an automobile or other machinery upon which work is to be performed.

Second, to provide an improved portable support which is capable of complete adjustment and at the same time is simple in 25 structure and can be easily manipulated.

Further objects, and objects relating to structural details, will definitely appear from the detailed description to follow.

30 I accomplish the objects of my invention by the devices and means described in the following specification. The invention is clearly defined and pointed out in the claim.

35 A structure which is a preferred embodiment of my invention is clearly illustrated in the accompanying drawing forming a part of this specification, in which:

Figure I is a side view of a structure embodying the features of my invention, one 40 adjustment of the lamp engaging clamp being indicated by dotted lines.

Fig. II is an enlarged detail section on a line corresponding to line 2—2 of Fig. I, 45 showing details of the swivel member and its mounting.

Fig. III is a detail section on a line corresponding to line 3—3 of Fig. I.

In the drawing similar reference characters refer to similar parts throughout the 50 several views, and the sectional views are taken looking in the direction of the little arrows at the ends of the section lines.

Referring to the drawing, the spring support 55 engaging clamp 1 is formed of wire

and has spring coils 2. Its arms are crossed at 3 so that its jaws 4 are urged upon a support as 5. The lamp 6 shown is of the incandescent type provided with the cord 7, the lamp engaging clamp 8 being adapted to embrace or receive the lamp socket 9. The clamp 8 is provided with a pivot 10 which engages the bearing 11 of the swivel member 12. This swivel member 12 is formed of a piece of sheet metal folded 60 upon itself and conformed at 13 to provide the pivot bearing, its arms having curved corrugations 14 therein providing outwardly facing grooves engaged with the coils 2 of the support engaging clamp 70 whereby the member 12 is supported for sliding adjustment upon the supporting clamp 1. This permits of the lamp supporting clamp being adjusted to various angles relative to the supporting clamp 1, and being swiveled on the swivel member may be adjusted to various positions thereon.

My improved support is particularly adapted by me for supporting lamps but is desirable for use in other relations. As a 80 lamp support it may be secured in position to properly illuminate the part of a machine upon which the mechanic is working, such as the parts of an automobile, or upon the person of the worker, or upon a reading 85 lamp, or upon a bed, chair or other support as desired.

Having thus described my invention, what I claim as new and desire to secure by Letters Patent is:

In a portable support, the combination of 90 a spring support engaging clamp provided with a spring coil at its bight end, an article engaging member provided with a laterally projecting pivot, and a swivel member 95 formed of a piece of sheet metal folded upon itself to provide a bearing at its bight end for said pivot, and having curved corrugations in its arms providing outwardly facing grooves engaged with said coil of 100 said support engaging clamp for sliding adjustment therein.

In witness whereof, I have hereunto set my hand and seal in the presence of two witnesses.

FRANK P. D'ARCY. [L.S.]
